REAR VISION MIRROR FOR VEHICLES

George N. Barney, Toledo, Ohio

Application January 31, 1956, Serial No. 39,984

Term of patent 14 years

(Cl. D14—6)

Figure 1 is a perspective view of the rear vision mirror for vehicles showing my new design;

Figure 2 is a front elevational view; and

Figure 3 is a side elevational view thereof.

The dominant feature of my design resides in the full line portion of the drawing.

I claim:

The ornamental design for a rear vision mirror for vehicles, substantially as shown and described.
